UNITED STATES PATENT OFFICE.

EDMUND R. BARANY, OF BROOKLYN, NEW YORK, ASSIGNOR TO FRANCO ELECTRIC CORPORATION, A CORPORATION OF NEW YORK.

FLASH-LIGHT-BULB SUPPORT.

Application filed August 14, 1922. Serial No. 581,598.

To all whom it may concern:

Be it known that I, EDMUND R. BARANY, a citizen of the United States, residing in the borough of Brooklyn, county of Kings, 5 city and State of New York, have invented certain new and useful Improvements in Flash-Light-Bulb Supports, of which the following is a specification.

This invention relates to flashlight bulb 10 supports.

An important object of my invention is to provide a support of the character mentioned, which is so constructed as to relieve the electric bulb from any excessive shock 15 or impact which may be imparted thereto upon an accidental, or otherwise, undue longitudinal displacement of the battery within the flashlight casing.

A further object of my invention is to 20 provide a support of the character mentioned in the form of a unitary structure, which is inexpensive to manufacture, easily assembled and reliable in use.

Other objects and certain advantages of 25 the invention will become apparent from the following description when taken in connection with the accompanying drawings, in which—

Figure 1 is a side elevation of a flashlight, 30 a portion thereof being broken away to illustrate the several elements of the support embodying my invention.

Figure 2 is a top plan view of the support.

Figure 3 is a bottom plan view of the support shown in Figure 2.

Figure 4 is a view in perspective showing the several elements of the support in their order of assembly.

In the drawings, wherein for the purpose of illustration is shown what I at present consider the preferred form of my invention, the numeral 5 indicates an elongated casing or housing, adapted to receive there-in the usual form of battery 6, having a carbon electrode 7. The casing, as shown, is provided with a conventional form of head 8 having screw threaded engagement with the casing 5 and provided with the conventional type of lens 9 and lens ring 10.

The support embodying my invention is illustrated as a whole by the numeral 11 and is adapted to be suitably retained within the head 8 as a means for supporting an

electric bulb 12, having an outer contact 55 13 and a central contact 14.

In constructing the device embodying my invention, I employ a fiber washer 15, having a central opening 16, adapted to receive a screw threaded socket 17, which is preferably formed integral with a metallic plate 18, suitably connected to the washer 15, as by means of rivets 19, which are also utilized to retain a similar insulating washer 19 in a correct position upon the lower face 60 of the plate 18. This washer is provided with a central opening 20, to receive the central contact 14 adapted to engage a resilient tongue 21, struck up from a metallic conductor plate 22, with which is associated 65 a similar plate 23, having a resilient tongue 24 struck therefrom, adapted to electrically engage the central contact 7 of the battery. The plates 22 and 23 are provided at corresponding ends with openings 25 and 26, respectively, to accommodate rivets 27, which are utilized to retain the plates in their respective positions upon the washer 19, the rivets being passed through the insulating washer 15, and relatively large 70 openings 28, provided in the plate 18, the openings 28 being somewhat larger than the rivets 27 for the purpose of preventing short circuiting between the battery 6 and bulb 12 as will be readily appreciated.

The circuit through the bulb 12 is adapted to be controlled by the usual form of switch 29, carried by the casing 5, to which is suitably connected a conductor 30 having electrical engagement with the plate 18 at or 75 relatively near the peripheral edge thereof. In tracing the circuit through the lamp, it will be observed that the current passes from the electrode 7 through the resilient tongue 24, the plates 22 and 23, the resilient tongue 21, into the lamp 12 through the central contact 14, and out of the same by way of the outer contact 13, from whence it passes through the sleeve 17, and plate 18, to the conductor 30, which is adapted to be electrically connected with or disconnected from the usual form of zinc electrode of the battery by means of the circuit controlling switch 29.

With the device embodying my invention, it is apparent that when the bulb 12 is run down into engagement with the tongue 21,

the same is permitted to slightly yield when a further thrust is exerted thereupon, and that such resiliency as the tongue 21 might possess may be utilized to insure a positive 5 electrical connection under all conditions between the central contact 14 of the bulb and the plate 22.

It will be further observed that the bulb 12, in its entirety, may be relieved of any 10 excessive shock which might otherwise result from undue displacement of the battery 6 within the container 5, since the tongue 24 is adapted to yield to a material degree, due to its inherent resiliency, when 15 a longitudinal thrust is exerted upon the battery in the direction of the flashlight head.

Having thus described my invention, I claim:

- 20 1. In a flashlight having a bulb and a battery, a bulb support disposed intermediate said bulb and battery comprising a plate having a screw threaded sleeve adapted to receive said bulb, a pair of plates 25 having electric connection with each other, resilient tongues carried by said plates, one of said tongues being adapted to electrically engage the central contact of said bulb whereas the other of said tongues is adapted 30 to electrically engage one of the electrodes of said battery, and means for insulating the first mentioned plate from said pair of plates.
- 25 2. In a flashlight having a bulb and a battery, a bulb support disposed intermediate said bulb and battery, comprising a plate having a screw threaded sleeve adapted to receive said bulb, a pair of plates having electric connection with each other, 35 resilient tongues carried by said plates, one of said tongues being adapted to electrically engage the central contact of said bulb whereas the other of said tongues is adapted 40 to electrically engage one of the electrodes of said battery, means for insulating the first mentioned plate from said pair of plates, and means for electrically connecting the first mentioned plate with said battery.
- 40 3. In a flashlight having a bulb and a battery, a bulb support disposed intermediate said bulb and battery comprising an insulating disc, a plate associated with said disk and having a screw threaded portion 45 adapted to receive said bulb, and a pair of electrically connected resilient tongues associated with said disk, one of which is adapted to engage the central contact of said bulb whereas the other is adapted to 50 electrically engage one of the electrodes of said battery.
- 50 4. In a flashlight having a bulb and a battery, a bulb support disposed intermediate said bulb and battery comprising an insulating disc, a plate associated with 55

said disk and having a screw threaded portion adapted to receive said bulb, a pair of electrically connected resilient tongues associated with said disk, one of which is adapted to engage the central contact of 70 said bulb whereas the other is adapted to electrically engage one of the electrodes of said battery, and means for insulating said tongues from said plate.

5. In a flashlight having a bulb and a 75 battery, a bulb support disposed intermediate said bulb and battery comprising an insulating disc, a plate associated with said disk and having a screw threaded portion adapted to receive said bulb, a pair of electrically connected resilient tongues associated with said disk, one of which is adapted to engage the central contact of said bulb whereas the other is adapted to electrically 80 engage one of the electrodes of said battery, means for insulating said tongues from said plate, and means for electrically connecting said plate with said battery.

6. In a flashlight having an electrical bulb and battery, a support for said bulb comprising a disc of insulating material, a plate having a screw threaded sleeve adapted to receive said bulb, a pair of metallic strips having resilient tongues struck therefrom, one of which is adapted to electrically engage the central contact of said bulb whereas the other is adapted to electrically engage one of the electrodes of said battery, and a second disc of insulating material disposed between said plate and said metallic strips and having an opening adapted to permit electrical contact between one of said tongues and the central contact of said bulb.

7. In a flashlight having a bulb and a 105 battery, a bulb support disposed intermediate said battery and bulb comprising a pair of electrically connected plates having contact elements struck therefrom, one of said contact elements being adapted to electrically engage the central contact of said bulb whereas the other of said contact elements is adapted to electrically engage one of the electrodes of said battery, a plate associated with said pair of plates and having a screwthreaded sleeve adapted to receive said bulb and an insulating member disposed intermediate said pair of plates and said plate having said screwthreaded sleeve associated therewith.

8. In a flashlight having a bulb and a battery, a bulb support disposed intermediate said battery and bulb comprising a pair of electrically connected plates having contact elements struck therefrom, one of said contact elements being adapted to electrically engage the central contact of said bulb whereas the other of said contact elements is adapted to electrically engage one of the electrodes of said battery, a plate associat- 125

ed with said pair of plates and having a screwthreaded sleeve adapted to receive said bulb and an insulating member disposed intermediate said pair of plates and 5 said plate having said screwthreaded sleeve associated therewith, said insulating member being provided with an opening adapted to receive the central contact of said bulb whereby electrical connection is established directly between said bulb and one 10 of said contact elements.

9. In a flashlight having an electric bulb and battery, a bulb support disposed intermediate said battery and bulb comprising 15 a pair of metallic plates arranged one upon the other and having contact elements struck therefrom, one of said elements being adapt-

ed to electrically engage the central contact of said bulb whereas the other of said elements is adapted to electrically 20 engage one of the electrodes of said battery, an insulating member superimposed upon said plates, a metallic plate superimposed upon said insulating member and having a bulb receiving socket, an insulating member 25 superimposed upon said metallic plate and surrounding said bulb receiving socket and means for uniting said pair of plates, said insulating members and said metallic plate together in a unitary structure.

In testimony whereof, I have affixed my signature to this specification.

EDMUND R. BARANY.
